Primary Examiner — Mark A Goodwin(74) *Attorney, Agent, or Firm* — KLINTWORTH & ROZENBLAT LLP(57) **CLAIM**

The ornamental design for a tank assembly for work vehicle, as shown and described.

DESCRIPTION

FIG. 1 is a rear perspective view of a tank assembly for work vehicle according to our new design;

FIG. 2 is a left side elevational view thereof;

FIG. 3 is a right side elevational view thereof;

FIG. 4 is a front elevational view thereof;

FIG. 5 is a rear elevational view thereof;

FIG. 6 is a top plan view thereof;

FIG. 7 is a bottom plan view thereof; and,

FIG. 8 is a rear perspective view of a tank assembly for work vehicle according to another embodiment of our new design, the various views thereof being mirror images of FIGS. 2-7.

1 Claim, 8 Drawing Sheets(56)
